UNITED STATES PATENT OFFICE.

MAX GREENBLATT, OF NEW YORK, N. Y.

SLIPPER.

Application filed July 14, 1924. Serial No. 725,792.

To all whom it may concern:

Be it known that I, MAX GREENBLATT, a citizen of the United States, residing at New York city, in the county of Bronx and State of New York, have invented certain new and useful Improvements in Slippers, of which the following is a specification.

My invention relates to a new and improved slipper.

10 One of the objects of my invention is to devise a new and improved slipper having an upper made of some soft fabric, which will be so constructed so that the said fabric will remain in shape.

15 Another object of my invention is to devise a slipper of this type in which the soft upper will be connected at the rear portion thereof below the top of the heel, to the lower part of said slipper so that the pressure of the foot of the wearer cannot injure the upper.

20 Another object of my invention is to devise a slipper of this type having an up- raised rear or heel portion so as to provide 25 a comfortable and durable construction.

Other objects of my invention will be set forth in the following description and drawings which illustrate a preferred embodiment thereof.

20 Fig. 1 is a longitudinal sectional view.
Fig. 2 is a top view.

Fig. 3 is a section on the line 3—3 of Fig. 1.

35 Fig. 4 is a plan view of the bottom of the shoe.

The slipper is provided with a bottom sole 13 and a top sole 11. A bottom heel portion 14 can be provided if desired, although this is not essential for my invention.

40 I prefer to raise the rear or heel portion of the upper sole 11, by means of a wedge-shaped insert 12.

45 The rear of the shoe can be raised in any other suitable manner, but I prefer the construction above mentioned as it is simple and easy to manufacture.

The top sole 11 can extend substantially to the toe of the shoe as shown in Fig. 1 but it would not be departing from my invention if the top sole 11 were made shorter and did not extend to the toe of the shoe.

50 The bottom sole 13 and the heel portion 14 are enclosed by a fabric-facing 15 clearly shown in Fig. 3 and the top sole 11 together with the insert 12, which may be

called a heel-lift, are enclosed by an upper fabric-facing 16 which covers the top of the upper sole 11 as clearly shown in Fig. 3.

55 The upper 17 of the slipper or shoe, which is made of fabric or any other soft material, has the usual front portion 10 clearly shown in Fig. 2. This upper 17 has the rear portion thereof turned under as shown at 17' and this portion 17' is connected below the 60 top sole member 11 and between the insert 12 and the bottom sole member 13. In front of the insert 12 the front portion 10 of the upper 17 is connected in the ordinary manner.

65 The rear of the upper 10 may be left open as shown in Fig. 2 and a piece of elastic 18 may be utilized for connecting the separated ends of the upper 17.

70 Heretofore, in slippers or shoes of this type the wearer has often stepped upon the side of the upper, because of the softness of the article so that the upper became distorted in a very short time.

75 According to my invention the rear portion of the upper is free from and spaced from the raised heel portion so that the wearer steps at all times upon this raised heel portion and cannot step upon or twist or injure the soft upper.

80 The elastic 18 aids to keep the upper in proper shape.

85 The various parts of the shoe or slipper are connected to each other in the ordinary and well known manner as by sewing and the like.

90 I have shown a preferred embodiment of my invention but it is clear that numerous changes and omissions could be made without departing from its spirit.

95 I claim:

1. A slipper having two superposed sole portions at the rear thereof, an insert located intermediate said sole portions at the rear thereof and adapted to upwardly incline the 100 rear of the top sole portion, a fabric member stitched to said insert and to said upper sole, and an upper having the bottom thereof turned in intermediate said insert and the lower sole portion.

105 2. A slipper having an upper sole portion and a lower sole portion at the rear thereof, an insert located intermediate said sole portions at the rear thereof and adapted to upwardly incline the rear of said upper sole portion, a fabric facing adapted to 110 cover the upper surface of said upper sole

portion, the rear of said facing being turned in under said insert, another facing adapted to cover the bottom surface of said lower portion and having its ends turned in above the top of said bottom sole portion, and an upper having its ends inturned and located intermediate the inturned ends of said facing.

3. A slipper having an upper sole portion extending to the rear thereof, a wedge shaped lower sole portion extending to the rear thereof, a wedge shaped insert located at the rear of the slipper intermediate said sole portions, a fabric facing stitched to

said insert and said upper sole portion, said 15 fabric facing covering the top of said upper sole portion and having its ends turned inwardly under said insert, a second fabric facing covering the bottom of said lower sole portion and having its ends turned inwardly above the top thereof, and an upper having the ends of the rear thereof turned inwardly and located between the inturned ends of said facings.

In testimony whereof I hereunto affix my 25 signature.

MAX GREENBLATT.
